United States Patent Office.

WILLIAM A. TERRY, OF BRISTOL, CONNECTICUT.

Letters Patent No. 99,258, dated January 25, 1870.

IMPROVEMENT IN CLOCK-CALENDARS.

The Schedule referred to in these Letters Patent and making part of the same.

To all whom it may concern:

Be it known that I, WILLIAM A. TERRY, of Bristol, in the county of Hartford, and State of Connecticut, have invented a new and improved Calendar; and I hereby declare that the following is a full, clear, and exact description thereof, which will enable those skilled in the art to make and use the same, reference being had to the accompanying drawings, making a part of this specification, in which—

Figure 1 is a front view of the dial and pointer.

Figure 2 is a view of the week-day disk.

Figure 3 is a front elevation of the working-mechanism.

Figure 4 is a front elevation of the pointer.

Figure 5 is a side elevation of the same.

Figure 6 is a front view of the double-acting dog or pawl.

Figure 7 is a front view of the year-wheel and pinion.

Figure 8 is a front elevation of my invention, showing the position of the pawl *p*, as it engages with wheel *D*, and also showing the interposing lever holding the arm of the dog forward in position ready to be caught by the hook *e*.

Figure 9 is a front elevation of same, showing the position of part of the parts, when the pointer has nearly reached fig. 1 on the dial.

Similar letters of reference indicate like parts.

The invention is designed as an improvement on a calendar, patented by me, June 16, 1868.

The improvement consists in the peculiar mechanism for regulating the movement of the month-wheel, so that the index shall always register the proper number of days for the month shown on the dial, whether the pointer has been moved by hand or by the clock; also, in operating a calendar-mechanism by the strike, instead of the time-part of the clock.

It also consists of constructing the pointer of three pieces, to enable the same to be easily and cheaply fitted and held in place; also, in the employment of two disks, one over the other, with the names of the months on one, and the names of the days of the week on the other, both lists of names being nearly on the same circle, and arranged behind a disk provided with openings, so that the day of the week and the month in the year can both be seen at the same time.

A designates a disk, on which are marked the months of the year, and which disk is attached to the twelve-toothed year-wheel *C*, or connected with the same by means of a hollow arbor.

B designates the pointer attached to the arbor of the month-wheel *D*, which passes through the hollow arbor of the year-wheel *C*.

In figs. 3 and 8, the year-wheel *C* is partially re-

moved from the top of wheel *D*, so as to show the parts more clearly; a portion of it, however, is indicated in its proper position over wheel *D*.

E designates the main strike-wheel of an ordinary eight-day clock. This wheel *E* has upon it a pin, *c*, for moving and operating the calendar.

a a' designate a double-acting pawl or dog, pivoted to one of the spokes of wheel *D*, with both arms on the under side of said wheel.

One arm *a* is provided with a pin, *z*, which reaches through the openings between the spokes of wheel *D*, and also provided with a stop, *b*, to prevent the dog *a a'* from being moved beyond a certain point, without carrying the wheel *D* with it. If the pawl or dog *a a'* were placed in a different position, the pin *z* might be used for a stop, without the addition of another pin, or the end of the arm *a* might be turned up for the same purpose.

This pawl or dog *a a'* is for the purpose of taking up and passing over the extra teeth in the wheel *D*, for months of less than thirty-one days, and if wheel *D* have thirty-two teeth, it also serves to take up the thirty-second tooth of the month-wheel *D*, while the index changes for the next month.

The year-wheel *C* is provided with five pins *l l l l m*, placed in such positions that at the end of each month, before a month having less than thirty-one days, the end of the interposing or stop-lever *d* shall strike against the proper one of them, to regulate the position of the pawl *a a'*, so that it shall be taken up by the hook *e* at the proper time to give the right number of days in the following month. The pins *l* are for the thirty-day months, while the pin *m* is for February. The position of these pins over the wheel *D*, is shown by the small circles in fig. 3.

g designates a pinion attached to the bridge *F*, and gearing into the year-wheel *C*.

h designates a pin attached to the rim of the month-wheel *D*, which, at the end of each month, engages with the teeth of pinion *g*, and causes pinion *g* and year-wheel *C* to revolve sufficiently to bring the name of the following month immediately back of the opening *n* in the dial *G*.

f and *i* designate springs, one end of which presses upon the teeth of the wheels *D* and *C*, and prevents them from rotating unintentionally.

The axis upon which the wheel *D* is fixed, works inside that of wheel *C*.

H designates a lever, pivoted on the frame of the clock.

I designates a lever pivoted to the back plate *J* of the calendar, and connected by rod *o* to the lever *H*.

Lever *I* is provided with a pawl, *p*, and arms or hooks *q* and *e*.

Lever K, which can be pivoted to a bridge, as shown, or to the same centre shaft with the wheels D and C, rests upon arm g, and is provided with a pawl, r.

s designates a pin or stop secured to plate J, which pin strikes against the pawl p, and prevents it from engaging with the teeth of wheel D, so that said wheel can be turned backward, if desired.

To the under side of the stop-lever d is secured a curved arm, t, and on the plate J, and under the wheel D, is secured a pin, a², represented by small broken circles in fig. 3.

u designates spurs or arms, formed on the week-day disk L, the position of which spurs u is shown in fig. 3. This disk L is provided with seven openings, and the names of the days of the week are placed on the arms between the same. The names of day of the week being seven, it will be noticed that each name is opposite an opening on the same disk.

In cutting these, the spurs u are left, one of which is represented in fig. 2, which spurs are afterward bent backward at right angles with the disk L. The disk L is placed immediately back of the dial G, and in front of the disk A, so that the name of the day of the week will be seen through the opening r in dial G, and the name of the month, which is marked on the same-sized circle, will be seen at the right hand of the same, through the openings n in the dial G, and disk L, while the pointer B indicates the day of the month on the dial G.

To maintain the pointer B in its proper position on the socket, and also to secure the wheel C and disk A in their place I provide the pointer B with a brass socket, w, firmly secured to the same. On one side of the socket w, I make a small hole. The greater part of the socket should be on the under side of the pointer, to insure placing it on right-side up, and also to form a washer to secure disk A and wheel C on the arbor.

As the shaft to which the pointers are fitted varies in size, the pointer is fitted by reaming the socket w.

When properly fitted, a small pin, k, is driven into the hole in the socket, before mentioned, so as to project a little on the inside of the same, as shown in fig. 4. The end of the pin k enters the slot J, fig. 3, and insures placing the pointer always in its proper place. The wheels C and D, pinion g, springs f and i, pins h l l l l and m, and pawl or dog a a¹, are substantially the same as in the original patent.

The operation of my invention is as follows:

The strike main-wheel E of an ordinary eight-day clock revolves once every twenty-four hours. Other wheels in the strike-part might be arranged to propel the calendar, but this wheel is most convenient. As the clock ceases to strike eleven at night, the wheel E stops, with the pin e in the position shown in black in fig. 3. On striking twelve, the pin e carries the levers H, I, and K, into the positions shown in fig. 9. As the lever I rises above the pin s, the spring z throws the pawl p into position to engage with the teeth of the month-wheel D, as indicated in fig. 8, and moves the wheel D one tooth, and the pointer B indicates an advance of one day on the dial G. As the lever I rises, the pin q causes the lever K to rise with it, while the pawl r engages one of the spurs or arms u, and brings the succeeding day of the week immediately back of the opening r on the dial G. As the wheel D, each succeeding day, is moved on in its course, the pawl or dog a a¹ strikes the pin a² on the plate J, and throws its arm a¹ forward, and its arm a outward, until pin z engages with the outside of the curved arm t on the lever d, as shown in fig. 8. As the spring y, for holding the dog or pawl a a¹ in place, is stronger than the spring y¹, for holding the lever d in place, the lever d (if in a thirty-one-day month) is drawn inward so far, that when the pawl or dog a a¹ has passed the pin a², it is in the same position as it

would have been if the lever d and pin a² had not been in its course.

On the thirty-first day of the month, the pawl or dog a a¹ is advanced so far that the hook e engages with the arm a¹, and moves the dog on its pivot until the stop-pin b strikes the spoke of wheel C, as shown in fig. 9, when it turns the said wheel one tooth, in addition to the tooth which has just been moved by the pawl p, thus carrying the pointer, at one time, from 31 over the blank space to 1. If only thirty-one teeth, instead of thirty-two teeth, are used, (as could be, if desired,) this pawl or dog a a¹ would be arranged so as to move the wheel D in the short months only.

While the pawl p and hook e are moving the wheel D, the pin h engages with the teeth of pinion g, and causes the wheel C and disk A to make one-twelfth of a revolution, and the name of the succeeding month shows through the opening n in the dial G and disk L.

When the pin a² throws the pin z on the pawl or dog a a¹, outside of the curved arm t, (if in a short month,) the end of stop-lever d strikes one of pins l or m, and prevents the spring y from drawing the lever d inward, as shown in fig. 8; consequently, the arm a is further forward, and the stop-pin b nearer the spoke, (if on the February pin, it is three days or teeth further forward, and if on a thirty-day-month pin, one day or tooth of wheel D further forward,) and as the hook e engages with the arm a¹ one or three days sooner, it carries the wheel D and pointer B the requisite number of days further.

Although the hook e and arm a¹ engage from one to three days sooner, they always disengage at the same point, leaving the pointer B at fig. 1 on the dial G. This calendar not being calculated for leap-year, on that year, and that only, it will be necessary, on the first of March, to turn the pointer back one day or space.

Instead of being attached to the lever I, the pawl p and hooks q and e might be attached to a reciprocating slide, and produce the same effect.

The stop-lever d can be made of any form, and arranged in any other manner, provided it interposes between the arm of the pawl or dog a a¹ and the pins l or m, as and for the purpose described.

In the original, if the pointer were turned by hand, and left in a short month, it would count thirty-one days. By using the interposing or stop-lever d, the calendar will always count correctly for the month shown on the dial.

Ordinarily, calendars have been attached to the time-part of clocks. As the time-wheels are continually moving, a twenty-four-hour wheel, so attached, moves very slow, and, therefore, occupies several hours in moving the calendar each night, all of which time the calendar of the clock should not be touched. The necessary power thus taken from the time-part often causes the clock to stop. The strike-part, especially the main wheel, has generally considerable surplus power. As it moves but once an hour, or with an intermittent motion, it moves rapidly or instantaneously.

The calendar, being arranged to move while the clock is in the act of striking, is not connected to the clock but a few moments, and, consequently, can be altered or set any other time, when desired, and is not liable to stop the clock.

When a calendar-movement is attached to the time-part of the clock, it is necessary to notice the position of the twenty-four-hour wheel, and to set the pointer in such position that the said wheel will operate the calendar when the pointer is at twelve.

When attached to the strike-part, it is only necessary, in making the wheel E, to set the pin e in its proper position, and then arrange the clock so as to strike the proper hour indicated by the pointer, and the calendar will always be right. If designed to use this calendar on a clock with a time-part only, or for

other reasons, it can be attached to the time-part when desired.

The pointer B should never be turned backward after it has passed the twenty-sixth day of the month, or further than to carry it up to the first day of the month, but can be turned forward any time except while the clock strikes twelve at night.

By my invention I produce a calendar which can be turned either forward or backward, (except near the close of each month,) and will always count correctly for the month indicated on its face.

By placing the two disks one above the other, as large letters can be used on each disk as if only a single disk were used, the two thus occupying only the space of one. By connecting with the strike-part of the clock, many of the general objections to calendars are removed.

What I claim as new, and desire to secure by Letters Patent, is—

1. The combination of the pawl or dog a a' , the trip-pin a^2 , interposing lever d , and the wheels D and C, substantially as and for the purpose described.

2. The improved mechanism described, for operating a calendar-movement, consisting of the oscillating lever

I, carrying with it the pawl p , which engages with the teeth of wheel D, and moves the same one tooth each day, and the pawl or hook e , which engages with the pawl a^1 on the wheel D, at the end of each month, (or end of each short month,) and thereby moves said wheel one or more teeth in addition to that moved by the pawl p , substantially as described.

3. The week-disk L, constructed with each name opposite an opening therein, in combination with the month-disk A, and the dial G, concentrically mounted, so that the indications on the disk A are shown through the openings in the disk L, substantially as described.

4. The combination and arrangement of the pawl p , wheel D, and pointer B, the whole combined and arranged so that the pointer B can be rotated in either direction, substantially as and for the purpose described.

5. The combination of a calendar-mechanism with a clock-striking mechanism, so as to be operated thereby, substantially as and for the purposes described.

WM. A. TERRY.
